UNITED STATES PATENT OFFICE.

ALONZO E. RHODES, OF HOPEDALE, MASSACHUSETTS, ASSIGNEE TO DRAPER CORPORATION, OF HOPEDALE, MASSACHUSETTS, A CORPORATION OF MAINE.

AUTOMATIC FILLING-REPLENISHING LOOM.

1,351,189.

Specification of Letters Patent. Patented Aug. 31, 1920.

Application filed November 20, 1919. Serial No. 339,331.

To all whom it may concern:

Be it known that I, ALONZO E. RHODES, a citizen of the United States, residing at Hopedale, county of Worcester, State of Massachusetts, have invented an Improvement in Automatic Filling-Replenishing Looms, of which the following description, in connection with the accompanying drawing, is a specification, like characters on the

10 drawing representing like parts.

This invention relates to automatic filling replenishing looms wherein a magazine or hopper containing a supply of fresh filling carriers is provided and wherein upon the 15 call for filling replenishment a fresh filling carrier is transferred from this magazine or hopper to the lay. It sometimes happens that the supply of filling carriers in the magazine or hopper is allowed to run out. If 20 this happens, or if for any other reason a fresh filling carrier is not in position in the hopper ready for transfer upon the call for filling replenishment, it follows that when the call for replenishment occurs the mechanism will go through the operations of transfer but without transferring any fresh filling carrier from the hopper to the lay with the result that one or more picks of imperfect weaving will occur before the loom is 25 stopped.

It is the object of the present invention to provide a construction in which if, after a fresh filling carrier has been transferred from the hopper to the lay, the supply of 30 fresh filling carriers has become exhausted or for any other reason a fresh filling carrier is not brought into position ready for transfer that the loom shall then be stopped, thus enabling the operative to fill up the 35 hopper or properly position the filling carriers therein so that a fresh filling carrier will be in position for the next transfer.

In an application Serial No. 339,330, filed 40 concurrently herewith, I have disclosed an invention for securing this object embodied in a construction in which the stopping of the loom is effected through the agency of the usual warp stop motion employed on such looms, and have presented broad claims 45 to the invention.

The present invention is subordinate to the broad idea in the aforesaid application and is directed to a different means for securing the same result.

It is the object of the present invention 55 in the preferred form illustrated to provide a construction in which the stopping of the loom is effected when the condition referred to arises through the agency of the weft fork mechanism, and more particularly 60 through the agency of the weft fork at the filling replenishing side of a double fork loom.

These and other objects and features of 65 the invention will appear more fully from the accompanying description and drawings and will be particularly pointed out in the claims.

The drawings show a preferred form of 70 the invention embodied in an automatic filling replenishing loom of the well known Northrop type and of the double fork variety.

In the drawings—

Figure 1 is a plan view partially broken 75 away of a portion of the loom with a preferred form of the invention embodied therein.

Fig. 2 is a view in side elevation of a portion of the loom.

Fig. 3 is a view similar to Fig. 2 showing the feeler positioned to detect absence of 80 a fresh filling carrier from another position in the hopper.

The general construction and operation of 85 the Northrop type of automatic filling replenishing loom and the general construction and operation of a double fork loom of that type are both well known to those skilled in the art, and hence it will be necessary to describe only those features particularly related to the present invention.

The patent to Draper No. 853,199, granted 90 May 7, 1907, and the patents mentioned therein may serve as an illustration of this 95 type of double fork of the Northrop loom.

In the loom illustrated for embodying a preferred form of the present invention a breast beam 1 supports at the right hand side the hopper stand 2 in which revolves 100 the rotary hopper 3 carrying the supply of fresh filling carriers 4 arranged in a circular series of peripheral seats 5. This rotary hopper or feeder acts in the usual manner to bring the filling carriers successively to 105 transferring position which is the position in which the filling carrier 4 is shown in Fig. 2. This position is usually determined

by the butt of the filling carrier being brought by the rotation of the hopper into contact with a curved abutment 6.

When the running filling carrier has become wholly or partially exhausted suitable indicating mechanism sets in motion mechanism by which replenishment is effected by a transfer of a fresh filling carrier from the hopper to the lay 7 and by which the exhausted filling carrier is forced out through the lay. This transfer is usually effected by a transferrer 8 pivoted upon a stud 9 and which upon the call for filling replenishment swings downwardly forcing the filling carrier 4 resting against the abutment 6 out of the hopper on to the lay which is then located directly beneath.

It will be recognized that if a fresh filling carrier is not located beneath the transferrer or in position for transfer that the transferring mechanism will go through its motions without effecting any transfer, and the loom will continue to run with the exhausted filling carrier thus making one or more picks of imperfect cloth which it is highly desirable to avoid especially in the automatic filling replenishing loom provided with a feeler for detecting substantial exhaustion of filling in the running shuttle and effecting transfer before complete exhaustion takes place.

This difficulty is obviated by the present invention by means of a mechanism which stops the operation of the loom if the supply of filling carriers has become exhausted, or if a fresh filling carrier is not in position for transfer in the hopper, and in the preferred form illustrated this is effected through the weft fork mechanism and preferably through the right hand weft fork mechanism of a double fork loom.

The construction and operation of the weft fork mechanism of a double fork loom is fully disclosed in the patent to Draper. In the construction illustrated the left hand weft fork 10 when it is not tilted as by contact with the filling catches the hooked end of the vibrating weft hammer 11 and thus effects the forward movement of the fork 10 slide 12 and eventually in the usual manner operates the knock off lever 13 to throw the shipper handle 14 out of its retaining notch and allow it to spring to the end of its slot 15 and disconnect the driving power thus stopping the loom all in a familiar and well known manner. The action of the right hand weft fork 16 is similar. When it is not tilted, as by engagement with the filling, it catches the hooked end of an auxiliary vibrating weft hammer 17 and in a similar manner acts to effect the stopping of the loom. Various means are provided for delaying the action of the weft forks, and various constructions of weft fork mechanism are and have been provided, but as in the

present invention a full filling carrier has just been started in operation when the action of the present invention comes into play it is quite immaterial in what manner or in what degree of promptness the weft fork mechanism acts to stop the loom.

In the present invention the stud 9 for the transferrer is prolonged and carries rigidly mounted thereon a bracket 18. This bracket conveniently serves as a mounting for a tip support 19 for the filling carrier when in position for transfer. This tip support 19 is shown as pivoted at 20 upon the bracket 18 and normally held against a stop 21.

The bracket 18 is provided with a depending portion upon which is pivoted at 22 an upstanding arm 23. This arm has mounted therein by means of the set screw 24 and projecting rearwardly therefrom a feeler 25. This feeler is so positioned that its curved end rests against the top of the filling carrier 4 when it is in position in the hopper ready for transfer.

The arm 23 carrying the feeler is connected by a link 26 to an arm 27 secured by a set screw 28 to a shaft mounted at one end in the bracket 18 and extending along the front of the hopper stand and mounted at the other end in a bracket 30 extending up from the hopper stand. A helical spring 31 engaging at one end the bracket 18 and at the other end a collar 32 adjustably secured on the shaft 29 acts to rock the shaft to swing the feeler 25 downwardly. The shaft 29 adjacent the bracket 30 has clamped thereto by means of a clamp 33 an arm 34 extending rearwardly and bent laterally and rearwardly so that its free end rests over the looped end of one of the weft forks as for example the weft fork 16.

The operation will now be apparent. So long as a filling carrier 4 is in place in the hopper in position for transfer, the feeler 25 is held in its normal elevated position with the parts in the position shown in Fig. 2, and with the end of the arm 34 so far above the looped end of the weft fork as not to interfere with the action of the weft fork. If replenishment takes place and another filling carrier comes into position for transfer, the parts are retained in this position and nothing happens. If, however, transfer takes place and the supply of fresh filling carriers in the hopper has become exhausted or if for any other reason no fresh filling carrier comes into position for transfer, there is nothing to support the feeler 25 and it consequently through the action of gravity or aided by the spring 31 falls or swings about the pivot 22 downwardly and rearwardly. This results in moving the link 26 rearwardly, in rocking the shaft 29, and in lowering the end of the arm 34 into contact with the looped end of the filling

fork 16. The parts are so proportioned that when this takes place the looped end of the weft fork is held downwardly in position to be caught by the hooked end of the weft hammer. Consequently the weft fork mechanism is affected in the same manner as it would be by absence of filling in front of the fork, and consequently stopping of the loom is effected in the usual manner. As 10 already pointed out, it makes no difference how soon the loom stops and consequently it makes no difference just what is the action, whether delayed or not, of the weft fork mechanism because when the feeler 25 15 detects absence of a fresh filling carrier for the next transfer, a full filling carrier has just been transferred to, and is running on, the lay.

When the loom has been stopped under 20 the action of the mechanism of this invention the operative then replenishes the hopper or places a fresh filling carrier in position in the hopper ready for transfer and consequently no operation of the transferring mechanism can take place without a 25 fresh filling carrier actually being transferred.

In the construction illustrated Figs. 1 and 2 the feeler is shown as positioned to indicate the absence of a fresh filling carrier 30 from transferring position, but it is obvious that this is but one, although a preferred position, which the feeler may occupy and that its broad function in detecting a predetermined degree of depletion of the supply 35 of fresh filling carriers in the hopper or in detecting the absence of a fresh filling carrier at a predetermined point in the hopper may allow the feeler to detect at any 40 other predetermined point. In Fig. 3 the feeler 35 is shown as located to detect absence of the fresh filling carrier at a different predetermined position in the hopper.

Having thus described my invention what 45 I claim as new and desire to secure by Letters Patent is—

1. An automatic filling replenishing loom comprising a hopper containing a supply of fresh filling carriers for successive transfer 50 to the lay, means for detecting a predetermined depletion of said supply, loom stopping means, weft fork mechanism operative to effect actuation of the loom stopping means, and means controlled by the detecting action of the detecting means acting to render the weft fork mechanism operative to effect the actuation of the loom stopping means.

2. An automatic filling replenishing loom 60 comprising a hopper containing a supply of fresh filling carriers for successive transfer to the lay, means for detecting absence of a fresh filling carrier from position ready for transfer upon the call for filling replenish-

ment, loom stopping means, weft fork 65 mechanism operative to effect actuation of the loom stopping means, and means controlled by the detecting action of the detecting means acting to render the weft fork mechanism operative to effect the actuation 70 of the loom stopping means.

3. An automatic filling replenishing loom comprising a hopper containing a supply of fresh filling carriers for successive transfer to the lay, means for detecting a predetermined depletion of said supply, loom stopping means, a double weft fork mechanism operative through either weft fork to effect actuation of the loom stopping means, and means controlled by the detecting action 75 of the detecting means acting through the weft fork at the replenishing side of the loom to render the weft fork mechanism operative to effect the actuation of the loom stopping means. 80

4. An automatic filling replenishing loom comprising a hopper containing a supply of fresh filling carriers for successive transfer to the lay, a movable feeler held against movement by a filling carrier in position 90 in the hopper for transfer to the lay, loom stopping means, weft fork mechanism operative to effect actuation of the loom stopping means, and means controlled by the movement of the feeler resulting from absence of filling carrier in position of transfer to render the weft fork mechanism operative to effect the actuation of the loom stopping means. 95

5. An automatic filling replenishing loom 100 comprising a hopper containing a supply of fresh filling carriers for successive transfer to the lay, a feeler pivotally mounted adjacent to, and held against movement by, a filling carrier in position in the hopper for 105 transfer to the lay, loom stopping means, weft fork mechanism operative to effect actuation of the loom stopping means, a movable arm extending adjacent the weft fork mechanism and connected to and operated by the feeler upon movement thereof to render the weft fork mechanism operative to effect the actuation of the loom stopping means. 110

6. An automatic filling replenishing loom 115 comprising a hopper containing a supply of fresh filling carriers for successive transfer to the lay, a feeler pivotally mounted adjacent to, and held against movement by, a filling carrier in position in the hopper 120 for transfer to the lay, loom stopping means, weft fork mechanism including a weft fork tiltable into position to effect actuation of the loom stopping means, a movable arm extending over the weft fork, a rock shaft connected to and operated by the feeler and connected to and operating the said arm whereby movement of the feeler acts to tilt 125

the weft fork and thereby to render the weft fork mechanism operative to effect the actuation of the loom stopping means.

7. An automatic filling replenishing loom comprising a hopper containing a supply of fresh filling carriers for successive transfer to the lay, a transferrer stud, a bracket mounted upon said stud, a filling carrier tip support mounted on said bracket, a feeler 10 pivotally mounted on said bracket and held against movement by the tip of a filling car-

rier in position in the hopper for transfer to the lay, loom stopping means, and means for effecting the actuation of the loom stopping means by or through the movement of the feeler whereby absence of a fresh filling carrier from position in the hopper for transfer effects the stopping of the loom. 15

In testimony whereof I have signed my name to this specification.

ALONZO E. RHOADES.
